CUSHION STRUCTURE

Charles Edward Lenz, Baltimore, Md.

Application March 1, 1943, Serial No. 477,594

4 Claims. (Cl. 5—337)

This invention relates to cushion structures and more particularly to chair, seat, or other upholstered cushions constructed of fabric and fibrous material, without dependence upon the usual complement of metal springs customarily embodied in high grade upholstered cushions.

An object of the invention is to provide a cushion of the character referred to including a novel and improved arrangement of outer padding of fibrous material and a pre-formed inner core member or unit of fibrous material so shaped and so positioned relative to the outer padding of fibrous material as to impart to the complete cushion a desirable shape, resiliency, and resistance to becoming distorted or "set" after long use.

Another object of the invention is to provide a novel and improved core unit adapted to be embodied in cushions in a manner to provide the aforesigned desirable characteristics.

Other objects will become apparent from a reading of the following description, the appended claims, and the accompanying drawing, in which:

Figure 1 is a transverse sectional view of a cushion embodying the invention;

Figure 2 is a section on the line 2—2 of Figure 1 but showing only an inner core unit and omitting structure shown in Figure 1 as surrounding the core unit. Figure 2 is somewhat diagrammatic, showing layers of fibrous material in less compacted relation than they occupy in actual practice.

Figure 3 is a plan view of a pair of strips of fibrous batting or similar material laid lengthwise of each other preparatory to being rolled up for forming the core unit; and

Figure 4 is a fragmentary perspective view illustrating the relationship of the strips shown in Figure 3 after the rolling up operation has been just started.

In its general nature the cushion structure shown as illustrating one preferred embodiment of the invention comprises a central core unit A, a surrounding layered body B of resilient material, and a cover C of any suitable upholstery fabric. In the illustrative embodiment the cover C includes a top 1, bottom 2, which may be alike so that the cushion can be reversed, and sides 3 held together by stitching 4. It will be understood, however, that the invention does not reside in and is not limited to the particular form of the cover per se.

The core unit A, which itself preferably is of special construction as described hereinafter, preferably is of smaller overall dimensions than

the complete, covered cushion, the arrangement being such that the margins of the body B extend outwardly beyond the core unit A. The core unit is so formed as to taper from maximum thickness at its center to minimum thickness at its edges, and this shape, taken in connection with the outwardly extending marginal portions of the body B produces in the complete cushion a convexity, resiliency, and shape-restoring quality which is very desirable and advantageous.

The body B preferably includes a plurality of layers 5, 6, and 7 of fibrous material, such as cotton batting, above the core unit A and a plurality of layers 8, 9, and 10 of similar material below the unit A. The marginal portions of the layers preferably extend outwardly beyond all edges of the core unit A, the marginal portions of the layers 7 and 8 being substantially parallel to and adjacent each other. Preferably all of the layers extend completely across the space between opposite side edges 3 of the cover C. The layers 5—10 and hence the complete cushion derive a smoothly curved convex shape from the convex shape of the pre-formed core unit A taken in connection with the extension of the layers beyond the edges of the unit A.

The number and thickness of the layers of body material above and below the core unit A may be varied according to several factors, e. g. 30 the size of the complete cushion, the thickness of batting or other layer material to be used, and the quality or characteristics of the batting material. The commercial manufacture of a large number of cushions of a size suitable for the 35 average upholstered chair has indicated that best results may be obtained by using three pre-formed layers of cotton batting of a rather closely compacted or "felted" nature both above and below the core unit A.

40 In accordance with the invention the core unit A is, in itself, of a novel and improved construction. As shown in Figures 2, 3, and 4 it preferably is formed of two tapered strips 11 and 12 of fibrous material such as cotton batting, flat-45 rolled into an assembly which is convex or dome-shaped both top and bottom. In forming the assembly, the strips 11 and 12 are laid lengthwise of each other with the narrower end 11^a of the strip 11 adjacent the wider end 12^b of the strip 12, and with the wider end 11^b of the strip 11 adjacent the narrower end 12^a of the strip 12 (see Figure 3). A fold or "flat-roll" is then 50 formed as indicated at 13 in Figure 4, and the two strips then are rolled up completely. It will be seen that in the rolled-up assembly there is more

fibrous material at the central portion than at the edges, the result being to give the unit A the desired dome shape, tapering from maximum thickness at the center to minimum thickness at the edges.

The rolled up assembly of the strips 11 and 12 is encased by an upper sheet 14 of batting and a lower sheet 15 of batting, the sheets 14 and 15 being stitched together as at 16 just beyond the edges of the rolled strips 11 and 12. Preferably the sheet 15 is faced with a sheet 17 of fabric such as ordinary cotton gauze through which the stitching 16 passes. The sheet 14 may be faced with sized cotton batting indicated at 18 through which the stitching 16 passes.

As shown in Figure 1, the sized sheet batting 18 has thin marginal anchoring portions 18^a extending beyond two opposite edges of the body of the unit A. The anchoring portions are interleaved between the outwardly extending marginal portions of the layers 7 and 8 of the body B, the portions 18^a being, in effect, squeezed or held between the layers 7 and 8, thereby maintaining the unit A centered with respect to the body B.

Cushions embodying a core unit in the manner disclosed above are very comfortable as established by actual normal use. Cushions embodying the invention and which have been subjected to thousands of repeated mechanically applied loadings and unloadings have exhibited almost complete lack of any tendency to become permanently distorted or "set." They retain their original smoothly convex surfaces under the hardest use. This is attributable largely to the incorporation in the complete cushion of a core unit which is of dome shape, and to the construction of the core unit itself. The rolling of the material forming the core unit disposes the fibres thereof in multitudinous directions instead of allowing them to extend more or less all in the same general direction. This enhances the unit's resiliency and shape-restoring characteristics horizontally as well as vertically and makes for increased comfort and long life. The batting or like material used in forming the core unit A may be and preferably is less dense and less closely compacted than the more felt-like material in the layer structure B. This too results in great resiliency and shape-restoring characteristics, and reduces the weight of the complete cushion because the core unit displaces

a weight of layer structure B greater than the weight of the core unit itself.

The cushion structure disclosed embodies the invention in the form now preferred but it will be understood that changes may be made without departing from the invention as defined in the claims.

I claim:

1. In a cushion, a pre-formed resilient core unit of smaller overall dimensions than the complete cushion, said unit comprising a rolled assembly including two similarly tapered strips of fibrous batting laid together lengthwise of each other with the narrower end of each adjacent the wider end of the other respectively; a plurality of layers of resilient material both above and below said core unit and having marginal portions extending outwardly beyond the edges of the core unit; and a cover enclosing said layers and said core unit with the marginal portions of the two of said layers which are respectively adjacent the top and bottom of the core unit being substantially parallel to and adjacent each other.
2. In a cushion, a pre-formed resilient core unit of smaller overall dimensions than the complete cushion, said unit comprising a rolled assembly including two similarly tapered strips of fibrous batting laid together lengthwise of each other with the narrower end of each adjacent the wider end of the other respectively; at least one layer of resilient material both above and below said core unit and having marginal portions extending outwardly beyond the edges of the core unit; and a cover enclosing said layers and said core unit with the marginal portions of said layers being substantially parallel to and adjacent each other.

3. A pre-formed resilient core unit for a cushion, said unit including a rolled assembly of two similarly tapered strips of fibrous material laid together lengthwise of each other with the narrower end of each disposed adjacent the wider end of the other respectively.

4. A pre-formed resilient core unit for a cushion, said unit including a rolled assembly of two similarly tapered strips of fibrous batting material laid together lengthwise of each other with the narrower end of each disposed adjacent the wider end of the other respectively; and means for maintaining said strips in rolled up assembly.

CHARLES EDWARD LENZ.
